PACKING AND DISPLAY CONTAINER

Morris M. Einson, Yonkers, N. Y., and Arnold J. Tanner, North Haven, Conn.

Application May 31, 1934, Serial No. 728,290

8 Claims. (Cl. 206—44)

The present invention relates to folding boxes useful for packing and displaying merchandise and has particular relation to a well-known type of box wherein the merchandise is contained within two separate sections or members, so constructed and arranged that one member telescopes within the other. The purpose of such an arrangement is to permit one member, usually the rear one to be raised to an elevated position relatively to the other member so as to produce a tier like display effect for the merchandise.

The object of the invention is to introduce certain new and useful improvements so as to produce a more efficient packing and display means and at the same time reduce the cost of manufacture of the container. Another feature of the improved means is that therewith the operation of setting up the container is simplified both for packing and display purposes and still another advantage of the improved construction is that the improved container when set up for display will offer the maximum display value for the merchandise contained therein.

It is understood by those skilled in the art pertaining to the designing and manufacture of folding boxes that conditions vary a great deal as regards the box structure to meet the varying requirements for packing merchandise which are of variable weight and dimension and another important advantage with the new construction is that having the improvements herein described, the container may be easily designed to meet practically any requirement.

Several embodiments of the invention will be hereinafter more fully described with reference to the accompanying drawings wherein—

Fig. 1 is a perspective view showing the improved container, by full lines, in a closed position and with the cover, shown by broken lines, in the open position;

Fig. 2 is a perspective view showing the improved container in the set-up or displaying position;

Fig. 3 is a plan view of the blank from which the rear or sliding member is composed;

Fig. 4 is a sectional view taken on the line 3—3 of Fig. 2;

Fig. 5 is a plan view of the blank from which the outer member of the container is composed;

Fig. 6 is a plan view of a modified form of the container blank; and

Fig. 7 is a sectional view of a container constructed from the last mentioned blank.

Referring to said drawings, the improved container as illustrated is composed of the outer section A and the inner section B which are respectively composed of the blanks A—1 and B—1. In both instances the blank is in one piece cut and scored so as to permit folding into the condition for use. Blank B—1 is folded so as to form the front wall 4, rear wall 2 and side walls 3. The ends of the blank are folded together first by an automatic machine so that the glue lap 4 is united with the opposite end 5 in the usual way. The portion 1 has a depending flap 5 connected thereto which folds to form part of the bottom closure means for the container. The portion forming the back wall has depending therefrom flap 6 which provides another part of the bottom closing means. Portions 3 forming the side walls have depending therefrom a divided flap 7. The flap 6 has an extension 8 and this extension carries a tab 9. The top edge of the side wall forming portions 3 is notched as at 10. The construction of the blank has been described and hereinafter the use or purpose of the various details referred to will be described.

Blank B—1 forming the inner or rear sliding member is also a single piece blank which is cut and scored to provide a structure having side wall forming portions 11; portion 12 forms the back wall, portion 13 forms the bottom and portion 14 forms a display card. The side forming portions 11 are cut and scored to form folding wings 15. The side walls 11 are connected with the display card portion 14 by fillet piece 16 which folds on the crease lines α and β . The side forming pieces 11 have depending therefrom tabs 16' which are engaged in the slits 17 when the blank is set up.

A complete container composed of the blanks above described may require an outer or additional shell or cover to make the package secure for shipping purposes but with the blank shown in Fig. 6 a modification is embodied which consists of the triple folding extension 18 folding over the top and front of the container when in a closing position and when so folded, the end 19 lies under the bottom of the container with 50

- the extreme end 20 engaged so as to retain the so formed cover in a closed position. Otherwise the structure of the blank C is the same as blank B-1.
- 5 In assembling the blanks to form the set-up container blank B-1 is folded by first bringing the side forming portions 11 into a position at right angles to portion 12 and then the retaining tabs 16 are folded inwardly so that the ends thereof are engaged in the slits 17. The blank A-1 is folded to form the set-up structure by bringing it into the position from the flat folded position as it is in when delivered by the automatic folding and glueing machine. The tabs or tongues 7 are folded inwardly and separately and the next operation is to tuck in the flap 5 so that it will lie over the adjacent tongues 7. The flap 8 is then tucked in over the tongues 7 adjacent thereto so that flap 8 will stand erect within the formed container body A and operate as a partition. The body B is then placed within the shell or container member A as shown in Fig. 3 so that the front thereof bears against the back of the erect flap or partition 8. When so folded 25 the container is ready to receive the merchandise and when packed the cover or display portion 14 of the blank B-1 is folded so as to lie on top of the merchandise in the container, and which merchandise in the packed condition of the container is all on the same level. It should be noted that the blank B-1 is folded so that the prepared or decorated surface is on the inside and through this arrangement the printed surface of the display card 14 and the supporting wings 15 30 is shown from the front. When the display card is folded down the fillet 16 folds inwardly so that the cover will lie flush on top of the container.
- In the operation for setting up the packed container, the inner member is brought from the 40 down position as shown in Fig. 7 to the raised position as shown in Fig. 3. When the cover is down the fillet 16 lies in the flat position and when the cover is raised said fillet is raised and the portion thereof above the crease line b is folded outwardly so as to provide flanges and thereby provide a stiffened support to maintain the show card in a perfectly rigid upright position. The wings 15 are spread outwardly as shown in Fig. 2 and the lower edges thereof fit into the notches 10 whereby the inner member 45 is effectually held against any rocking movement. Further to prevent the displacement of member B the back face of the flap 8 bears against the bottom end of the member B and also the lower edge of the bottom forming portion 13. To reinforce this edge the additional and upwardly folding end 21 as shown in Fig. 6 may be employed.
- 50 In some instances it may be desired to limit the upward sliding movement of the member B and for this purpose the tab 9 is provided at the end of flap 8, so as to engage when folded inwardly, with the edge of the bottom 13 as shown more clearly in Fig. 7.
- 65 The inwardly tucked flap 8 has an advantage other than serving as a retainer for the inner member B, for it will be noted that as shown in the views of the assembled blank, that the printed surface only thereof is exposed when the 70 contents are removed from the compartment formed between the cut-out front wall of the container A and said flap 8. In this connection it should be noted the blanks A'-B' throughout are designed so that stock printed on one side only is necessary for all the surfaces of the

container prominently exposed are on the same side as the stock used.

When the container is set up for display the outer cover in the form of a sleeve or the like, if one is used, is first removed and when the modified blank as shown in Fig. 6 is used the triple folding flap is unfolded by first pulling out the end 20 engaged between the flaps 5-8 and then folding said extension reversely so that the portions 14, 18, 19 and 20 will be brought to the position as shown in Fig. 7 and in which position the printed or prepared surface is exposed in a front view of the display device.

In blank A' the flap 8 has partly cut notches 22 of which the uncut portion 23 may be folded 15 to furnish stops which will retain bottom closure flap 6 in an angular position and thereby provide a base which will support the container in an angular display position.

Various modifications may be made in carrying out the details of the invention hereinbefore described and it is to be understood that any modification coming fairly within the terms of the appended claims shall be covered thereby.

We claim:—

1. In a packing and display container of the class described an outer member, an inner member telescoping within said outer member, supporting means for retaining said inner member in a raised position relatively to said outer member, 30 said means comprising outwardly folding side wings or projections carried by said inner member arranged to engage the top edge of said outer member comprising an extended inwardly folding flap carried by said outer member and bearing against said inner member when said member is in a raised position, bottom closure means for said outer member and said flap co-operating with said supporting means to support said inner member in an upright raised position. 40

2. In a container according to claim 1, said outer member having bottom closure means comprising oppositely hinged flaps tucked in so that the ends thereof abut, and the end of one flap being extended to bear against the front of said 45 inner member.

3. In a container according to claim 1, said bottom closure means for said outer member comprising a tuck-in flap having an extended end bearing against said inner member and said extended end having an inwardly folding tab engaging said inner member to limit the upward movement thereof. 50

4. In a container according to claim 1, said bottom closure means for said outer member comprising oppositely connected tuck-in flaps and one of said flaps being retained in an adjusted position by stops to provide a support for the container in an angular position. 55

5. In a container according to claim 1, said inner member having angularly disposed, outwardly folding side wings engaging the top edge of said outer member whereby said inner member is retained in an elevated position. 60

6. In a container according to claim 1, said inner member being composed of a single sheet folded to provide a back wall, side walls and a bottom, wings or projections extending from said side walls and said wings or projections being arranged to engage notches in the edge of said outer member whereby said inner member is held in a determined raised position relatively to said outer member. 70

7. In a container according to claim 1, said inner member having an extension from the back 75

wall thereof adapted to be adjusted to operate as a cover for the container when closed and as an advertising card when the container is set up for display of contents.

5. 8. In a container according to claim 1, said inner member having an extension from the back wall thereof adapted to be adjusted to operate

as a cover for the container when closed and as an advertising card when the container is set up for display of contents, and means comprising a folding flanged, fillet for retaining said extension in a rigid upright position.
